EUGENE H. BROWN, OF BENNINGTON, VERMONT, ASSIGNOR TO THE UNION
RAVELER COMPANY, OF NORTH BENNINGTON, VERMONT.

TRIMMING AND RAVELING ATTACHMENT FOR MACHINES FOR SEWING LOOPED FABRICS.

SPECIFICATION forming part of Letters Patent No. 629,149, dated July 18, 1899.

Application filed January 26, 1893. Serial No. 459,791. (No model.)

To all whom it may concern:

Be it known that I, EUGENE H. BROWN, of the village of Bennington, in the county of Bennington and State of Vermont, have invented certain Improvements in Trimming and Raveling Attachments for Looping-Machines; and I do hereby declare that the subjoined description, taken in connection with the accompanying drawings, constitutes a specification thereof and of the best manner of constructing and using the same.

The invention is designed to be used in connection with machines commonly called "loopers," used in the manufacture of under-wear for attaching knit ribs to shirt-sleeves, drawer-bottoms, and shirt-bodies, and the function performed by it is to remove the surplus fabric projecting above the pins of the pin-wheel after the body cloth of the garment and the rib have been attached to the same and to pick or ravel out any adhering debris of the cut stitches after the pin-wheel has carried the fabric past the blade of the trimming-knife before it reaches the sewing-needle.

The invention belongs to that class of trimming-machines in which the loops of the course of stitches next above the impaled course are successively cut or severed by a pointed blade and the severed fragments of loops remaining adherent to the impaled stitches are subsequently removed by clearing devices. Letters Patent to Amos F. Champlin, No. 421,549, dated February 18, 1890, show a blade for cutting the loops which swings in a vertical plane and has a cutting edge turned upwardly which severs the loop entered by it at the center of its top, thus after each cut leaving two upstanding ends of the loop fragment which are of equal length. Being thus of equal length, it becomes more difficult for the clearing or raveling devices to seize one of these ends and miss the other than it would be if one of these ends were longer than the other. Hence if such a center-cut loop fragment happens to be caught by the clearing devices by both of its ends at the same time, the pulling or raveling action or stroke of those devices pulls up and often breaks the impaled stitches or loops off from the pins

of the pin-wheel on account of the enlacement of the loop fragment with the impaled loops, with the result that when the work is carried to the sewing-needle, the loops having been torn off the pins, there is nothing left for the sewing-thread to engage, and a gap in the seam is produced which has to be taken up or repaired by hand or a hole in the goods will be left. This difficulty is more apparent where every successive loop is cut than where every alternate loop is cut. In the present invention I turn the cutting-blade down on its side, so that it reciprocates in a horizontal plane, and thus cuts the loop entered by it at one side only, thereby leaving a short and a long upstanding end. The clearing-blades are adjusted to work in a horizontal plane at an elevation between the planes of the long and short ends of the loop fragments. As a result of this arrangement when the pin-wheel carries the loop fragments between the clearing-jaws they miss the short end of each loop fragment, but seize the long upstanding end and pull it out without resistance or damage to the impaled loops.

The invention is fully shown in the drawings, wherein the mechanism is shown in plan in Figure 1. Fig. 2 is a front elevation of the same. Fig. 3 is a vertical section taken through the axis of the cutter-slide and shows the relation of the raveler-fingers to the edge of the waste-trough, which part of the waste-trough thus forms the raveling-plate. Fig. 4 represents loop fragments produced by a vertical center cut. Fig. 5 represents loop fragments produced by cutting one side of the loop and shows a long and a short end to each severed fragment.

The apparatus consists of a small stand A, which is attached to the top plate T of the looper by the screws *a a*. A set-screw A⁴ passes through this plate and bears against the top of plate T for adjusting the angle of inclination of the stand with reference to the points or stitch-pins. This is done by loosening the screws *a a* and setting the adjusting-screw A⁴ as desired and then tightening it. To this base A an arched bracket B is attached, which is adapted to slide vertically thereon by means of the tongue *b*, which is

fitted to slide in the groove a^2 of the stand. The stand has two ears a' a' , between which the adjusting-screw K turns, the necking of the screw coming between the ears and the threaded part entering the threaded hole b^2 in the bracket. On the front upper surface of the bracket B is a stud h , to the top of which the lever G is pivoted. The other end of this lever is connected by a pitman H with the crank-disk H', which oscillates the arm T', that carries the sewing-needle T², so that it plays back and forth in unison therewith. The member which carries the blade J should reciprocate in unison with the intermittent movements of the pin-wheel, so that the point of the blade will enter and cut each loop while the pin-wheel is at rest, and such member may be connected with and actuated by any part of the driving mechanism which will 5 secure that result. Lever G has an elongated slot g , which takes in the driving-pin d' of the reciprocating slide D, which plays in a socket C, provided therefor, and attached to the bracket B. The front end of this slide D has 10 a cross-head d , to which the blade J and the raveling-fingers E are attached. The blade J is a steel plate of substantially the form shown drawn to a needle-point j for entering the second stitch above the point on the pin-wheel and gradually opening it for the admission of the knife-blade following it. By 15 reason of the horizontal position of this blade and its approximate parallelism with the plane of the pins it trims the fabric with a shaving stroke loop by loop without requiring any resisting support behind it, such draft or drag as may be put on the fabric by the cutting thrust of the blade being more nearly in a line parallel with the rim of the pin-wheel than across it. In this respect it differs from some existing machines in which the cutter-blade plays through a slot in a plate which supports the fabric. The horizontal position of the said blade is particularly important, because it enables the said blade to cut only one side of each loop above the impaled loops of the fabric, thereby leaving a loop fragment enlaced with the impaled loops which has a short and a long upstanding end, the latter of which passes along to the raveling-blades, between which it is seized and pulled out, while the short end passes under them out of their reach. The raveling device consists of a steel blade E, which may 20 be solid or slit into sections, like that shown in the drawings. In practice as the slide is reciprocated the front edge of the raveling blade or fingers plays against the beveled edge f of the waste-trough F or the raveling-plate and in doing so catches the aforesaid long ends and any adherent shreds or cut yarn retained by the loops on the pins and pulls them out. The opposed edges of blade E and plate F lie just above and in rear of 25 the loops on the pins. The blade E or the raveling-fingers are preferably made slightly elastic, so that if they engage a knot or other

excrecence on the yarn they will yield, if necessary. The waste-trough F is of dishing shape and of substantially the form shown, 70 so as to receive the severed selvage and any ravelings detached by the raveling-fingers, which consist, mainly, of the aforesaid detached loop fragments, and conducts them around and delivers them over the edge of 75 the rim of the machine and drops them out of the way. Another guide P is connected with the stand A by the screw p , the contour surface of which guide lies just above but in close proximity to the upper surface of the 80 pins, which serves to take the curl out of the edges of the cloth and to maintain its erect position as it approaches the blade. Beneath the arched bracket B is attached a spring-stock N, to which the guide-spring or deflector L is fastened. This guide-spring bears against the face of the fabric just below the pins of the pin-wheel, and its inner or bearing edge inclines from heel to point upwardly toward the pins. The gooseneck curve in the 85 stock N acts as a spring to throw the guide toward the rim of the pin-wheel and preserves a uniform and even contact therewith. The function of the guide-spring L is to draw the fabric down as it approaches the cutting-point and hold it tightly stretched as it is being trimmed, so that the action of the blade 90 will not pull the fabric up and fail to sever it properly or raise the loops on the pins high enough for them to be caught by the raveling-fingers and be damaged by them. 95

Just above the raveling-fingers an elastic clearing spring-guard W is placed, which is fastened to the bracket B, beneath the arch, as seen in dotted lines. This blade is so adjusted that its under edge lies just in front of the forward edge of the clearing-fingers, so that their forward stroke will lift the spring slightly and the back stroke will cause the under edge to scrape off into the waste-trough 100 F any and all lint-ravelings and loop fragments which might incline to adhere to the edges of the raveling-fingers. 105

The operation of the machine is as follows: The two pieces of fabric to be sewed together— 110 i. e., the body cloth and the rib—having first been run onto the pins and pressed back against the rim of the pin-wheel in the usual way and connection having been established between the end of the lever G and some reciprocating part of the apparatus acting in unison with the reciprocating needle T and the intermittent movement of the pin-wheel and the spring-guide L having been brought to bear fairly against the surface of the fabrics below the pins, the machine is started. 115 As the pin-wheel Q advances step by step the supporting-guide acts to keep the edges of the two pieces standing uprightly till they reach the blade J. Here the stroke of the 120 blade enters its leading point j through the cloth without rupturing the loop necessarily, but at the same time opening it, so that the 125 beveled edge of the blade can follow and cut 130

its way freely to the extent of its breadth from the point in the goods where it entered toward the needle or in that direction. The elevation of the blade above the pins is such that the cut is made through the course of loops next above the course run onto the pins, so that the cut fragments of yarn represent entire loops severed at one side, about one-half the length of each of which is enlaced with the loops, which are impaled on two adjacent pins, and the other half is left disengaged by the action of the blade and projecting upwardly directly across the path of movement of the raveling-fingers. As the cutting progresses the severed selvage falls back onto the plate F, where by the movement of the machine it is forced along and finally drops off the same onto the floor. When the trimmed edges reach the raveling-fingers as they pass along between them and the edge f of the plate F, the projecting or flying long ends of the loop fragments or ravelings are caught between the front edges of the fingers and the edge f of the plate F, while the short ends escape beneath and under the reciprocation of the slide are pulled out, or rather pushed out, and are swept along with the other waste over the plate F and out of the way. During this performance the spring L has held the cloth firmly drawn down; but as the cloth is fed along toward the needle it passes out from under said spring and contracts to its normal condition.

Special advantages accrue from using the blade in a horizontal position, so that the cutting plane shall be parallel with the plane of rotation of the pins. This position dispenses with the necessity of having a supporting-plate behind the fabric at the cutting-point, and such a back-supporting plate is dispensed with in this machine. Neither are any notches nor plates for the blade to play through necessary. With the cutting edge of the blade beveled or slanted back so that its leading point as it enters the loop is on the side toward the uncut fabric as it is pushed through the strain put on the goods in the trimming process is sustained by the sound or uncut fabric, supported by the pins upon which it is impaled, and is thus much more firmly held than when the cut or rupture is in a vertical direction. Besides, the liability of injuring the course of loops on the pins is greatly diminished. When a vertical blade is employed, the loop which is above the impaled loop of the fabric is cut through on top in each instance, leaving the two sides of the cut loop approximately equal in length. When the clearing-finger is brought into contact with them, it will often take hold of both together equally, and as they resist with equal force the pull on the uncut loops is apt to tear them; but my horizontal blade, severing at the side of the loop, close to the row of uncut impaled loops, will leave on one side only the entire part of any cut loop, and this side is easily caught by the clearing-finger and pulled free, the opposite

end of the loop notwithstanding high enough above the impaling-pins to be caught by the clearing devices. As there is a substantial interval between the point j and the clearing-finger after the blade has cut the side of a loop, the beveled heel of the blade on the next stroke will throw up the long end of the loop fragment, leaving it upstanding high above the short end, which promotes its seizure by the clearing-fingers. The effect on a particular loop of the first cut and of the successive blows of the blade upon the loosened end to throw it up in the path of the clearing-fingers is clearly shown in Fig. 5. The cutting stroke simply severs a loop, but leaves the terminal of the predestined long end still undetached from the web of the fabric. The next stroke draws it out, and subsequent strokes whip it up into a practically erect position where it cannot escape the clearing-jaws. This peculiarly-shaped blade fitted with the leading opening-point j also possesses advantages over a leading point produced by carrying the ground bevel of the cutting edge out to the extreme point, for the needle-point of this blade opens the loop without cutting or rupturing it in any way, thus leaving the cutting edge which follows it to sever the thread of a single loop without involving any other and without straining the loops on the points of the pin-wheel immediately underneath the blade. This leaves the trimmed margins of the two pieces of fabric in perfect integrity and entirely cleaned from waste, a condition especially to be desired.

I therefore claim as my invention—

1. In a machine for sewing looped fabrics, the combination with a pin-wheel having its pins for supporting the fabric disposed in a horizontal plane, of a trimming mechanism comprising a blade having a tapering point and a cutting edge laterally diverging from the base of said point, said blade being disposed in a plane that will cause its cutting edge to lie substantially parallel with the plane of the pins and close to and slightly above said pins, means for reciprocating said blade, and means for removing the severed loops from the fabric, whereby the point of said blade will first enter the loops to be cut and then the cutting edge will sever the said loops at one side only and close to the pins, to the end that said severed loops shall be of unequal lengths thus insuring their ready removal.

2. In a machine for sewing looped fabrics, the combination with a pin-wheel having its pins for supporting the fabric disposed in a horizontal plane, of a trimming mechanism comprising a blade having a tapering point and a cutting edge laterally diverging from the base of said point, said blade being disposed in a plane that will cause its cutting edge to lie substantially parallel with the plane of the pins, and opposite the row of loops next above the course of impaled loops, means for reciprocating said blade, whereby

the point of said blade will first enter the loops to be cut and then its cutting edge will sever the said loops at one side only, to the end that each severed loop fragment shall 5 present to the clearing or raveling devices ends of unequal lengths, the longer of which only passes into the field of action of the clearing devices.

3. The combination with the pin-wheel and 10 driving mechanism of a machine for sewing looped fabrics, of a loop-severing attachment embracing a needle-pointed blade possessing an edge adapted to sever a loop, a reciprocating member upon which said blade is 15 mounted with its cutting edge turned toward

one side of the center of the loop to be cut so as to sever the loops entered by it at one side only and close to the impaled loops, said reciprocating member being positively geared to said driving mechanism so as to synchronize with the intermittent movements of the pin-wheel, whereby the blade shall enter and cut the loops while the pin-wheel is at rest. 20

In testimony whereof I have hereto subscribed my name, at Bennington, Vermont, 25 this 3d day of September, 1892.

EUGENE H. BROWN.

In presence of—

FRANKLIN SCOTT,
EMILY SCOTT.
